UNITED STATES PATENT OFFICE.

THEODORE L. CAMP, OF CHICAGO, ILLINOIS, ASSIGNOR TO UNITED WRAPPING MACHINE COMPANY, OF CHICAGO, ILLINOIS, A CORPORATION.

WRAPPING-MACHINE.

No. 836,241.

Specification of Letters Patent.

Patented Nov. 20, 1906.

Application filed December 19, 1901. Renewed March 13, 1905. Serial No. 249,737.

To all whom it may concern:

Be it known that I, THEODORE L. CAMP, a citizen of the United States, and a resident of the city of Chicago, in the county of Cook and State of Illinois, have invented certain new and useful Improvements in Wrapping-Machines, of which the following is hereby declared to be a full, clear, and exact description.

The invention relates to machines for inclosing commercial articles or packages—such as boxes, cakes of soap, &c.—and more particularly to machines adapted to inclose articles in wrappers whereon is printed advertising or other matter.

The invention seeks to provide a construction in which the wrappers are fed from a continuous web, together with cutting and correcting mechanism, by which the separate wrappers are severed from the web in lengths corresponding to the separate printed portions thereof despite the slight variations in length of said printed portions and despite the slip of the feeding mechanism.

The invention further seeks to provide a machine in which the folding of the packages proceeds neatly, accurately, and rapidly and in which duplicate sets of folding mechanisms are employed and supplied with articles from a single feedway.

The invention consists in the features of construction, arrangement, and combinations of parts set forth in the following description, illustrated in the accompanying drawings, and more particularly pointed out in the appended claims.

In the drawings, Figure 1 is a plan view of the machine, certain parts being broken away. Fig. 2 is a longitudinal section of the machine through one of the wrapping mechanisms. Fig. 3 is a cross-section of the machine, certain parts being shown in elevation and certain parts being omitted for the sake of clearness. Fig. 3^a is a detail section on line *a a* of Fig. 3 of a part of the operating mechanism. Fig. 4 is a horizontal section through the machine below the top table, showing the operating-shafts and connections. Fig. 5 is a vertical elevation of the revoluble supports for the wrapper-webs and the feed for withdrawing the web therefrom. Fig. 5^a is a detail view of parts shown in Fig. 5. Fig. 6 is a section on line *b b* of Fig. 5. Fig. 7 is a detail plan view of the paper-feed

and correcting stop mechanism. Fig. 8 is a side elevation, and Fig. 8^a is a longitudinal section of the same. Fig. 9 is a detail rear view in elevation of a part of the correcting stop mechanism. Fig. 9^a is a detail side view in elevation of the electrical contacts by which the correcting stop mechanism is controlled. Fig. 9^b is a similar view of the opposite side, and Fig. 9^c is a section, on line *c c* of Fig. 9^a, of the same. Fig. 9^d is a diagram of the operating-circuit for the correcting stop mechanism. Fig. 10 is an enlarged detail plan view of the main set of feed-rolls and of the wrapper-guide chute. Fig. 10^a is a transverse section through the guide-chute on line *a a* of Fig. 10. Fig. 11 is a front elevation of the wrapper-feed rolls, the supporting-table being shown in cross-section. Fig. 11^a is a detail section on line *a a* of Fig. 11. Fig. 12 is a detail view in elevation, parts being shown in section, of the driving mechanism for the feed-rolls. Fig. 12^a is a detail side view of the connecting-gearing between the feed-rolls. Fig. 12^b is a detail side view, parts being shown in section, of the operating-gearing for the feed-rolls. Fig. 12^c and Fig. 12^d are detail end and side views, respectively, of the advance feed for the feed-rolls. Fig. 13 is a detail end view of the brake for the feed-rolls and its operating mechanism. Fig. 13^a is a side view of the same. Fig. 13^b is a detail view of a part of the brake-operating mechanism. Fig. 14 is a detail front view of the cutters for severing the separate wrappers from the web. Fig. 14^a is a plan view of the same. Fig. 14^b is a side view of the same, parts being shown in cross-section. Fig. 15 is a rear view of the cutting-knives. Fig. 15^a is a similar partial view of the cutting mechanism shown at the end of its forward stroke. Fig. 16 is a side view of the cutter and operating mechanism for said cutter and for the advance feed. Fig. 17 is a detail plan view of the machine, certain parts being omitted to show the side folders and the reciprocating guide for the wrapper-web. Fig. 18 is a detail plan view of the reciprocating guide-grip for the wrapper-web. Fig. 18^a is a detail end view of the same. Figs. 18^b, 18^c, and 18^d are detail sections, respectively, on lines *b b*, *c c*, and *d d* of Fig. 18. Fig. 19 is a detail plan view of the article-feed, certain parts being broken away. Fig. 20 is a detail transverse section through the machine, showing the article-feedway

and conveyer-belt. Fig. 21 is a detail sectional view showing the operating mechanism for the conveyer feed-belt. Fig. 21^a is a detail section on line *a a* of Figs. 17 and 19. 5 Fig. 21^b is a detail view of a circuit-closer for the operating-circuit of the correcting stop mechanism. Fig. 22 is a detail plan view of the folding-chute. Fig. 22^a is a transverse section of the same on line *a a* of Fig. 22. 10 Fig. 23 is a longitudinal section on line 23 23 of Fig. 22. Fig. 23^a is a view of one end of the folding-chute. Fig. 23^b is a view of the opposite end. Fig. 24 is a detail plan view of the operating mechanism beneath the table 15 for the side-folders. Fig. 24^a is a detail section on line *a a* of Fig. 24. Fig. 25 is a longitudinal section of the parts shown in Fig. 24. Fig. 26 is a detail plan view of the end-folders and operating connections. Fig. 27 is a longitudinal section of the parts shown in Fig. 20 26. Figs. 28, 28^a, 28^b, 28^c, 28^d, and 28^e are views illustrating the operation of the wrapping mechanism. Fig. 29 is a detail longitudinal section of the conveyer for carrying the 25 wrapped packages out of the machine. Fig. 29^a is a detail end view of the same.

The frame for supporting the various mechanisms of the machine, together with the drive-shaft and operating connections, 30 comprises the uprights or legs 30, upon the upper end of which is suitably mounted a table or bed-plate A. The legs or uprights 30 are connected (see Fig. 4) intermediate their ends by transverse members 31 and end 35 cross-pieces 32. Between the transverse members 31 extend the pairs of supporting cross-bars 33, 34, and 35. The uprights or legs 30, the transverse members 31, and supporting cross members 33, 34, and 35 are 40 preferably formed from angle-bars and securely connected together to provide a rigid frame. A main drive-shaft B extends transversely across the machine beneath the bed-plate A, is mounted in suitable bearings *b*, fixed, respectively, to the end pieces 32 and to 45 one of the cross members 34, and is provided on one end with a pulley *b'*, which may be coupled to any suitable source of power. A single wrapper may be employed; but the 50 machine is more particularly adapted for inclosing the articles in inner and outer wrappers of paper or other suitable material of the kind adapted and most generally employed for the particular articles to be wrapped. 55 For example, in wrapping soap (for which the machine illustrated is particularly designed) it is customary to employ an outer wrapper, of rather thin inexpensive paper, upon which is printed fanciful advertising or 60 other matter and an inner protecting-wrapper of stouter paper and of less width than the outer wrapper. It will of course be understood that the machine may be readily adapted for wrappers of any suitable material or width. 65

Beneath a pair of openings *a a'* (see Figs. 2, 3, and 17) are mounted a pair of folding boxes or chutes C C', within which the articles are held while being wrapped and above which the various mechanisms are grouped. The different mechanisms are preferably arranged in duplicate and so operated and timed that two packages will be formed at every revolution of the drive-shaft B. It will of course be understood that a single set of mechanisms could be employed, if desired. To the rear edge of the bed-plate A (see Figs. 1, 2, 5, and 6) are secured a pair of projecting supports 36, to each of which is bolted an upright 37. Lugs 38 upon the supports engage the uprights and hold them rigidly in position. Open hook-shaped bearings 39 are fixed to and laterally project from the upper and lower ends of the uprights 37, within which are removably and revolvably 85 mounted short supports or shafts D and E for the outer and inner wrapper-rolls *d* and *e*, respectively. These wrappers usually come from the printing-press in continuous webs of indeterminate length, rolled upon hollow 90 wooden mandrels 40, (see Fig. 2,) and in order that the wrapper-rolls may be mounted in accurate alinement with the means for withdrawing the wrapper-web therefrom the supports or shafts D and E are each provided 95 with a fixed cone 41 at one end and a removable cone 42, threaded upon the opposite end and arranged to engage the ends of the wooden mandrels upon which the wrapper-rolls *d* and *e* are mounted. As stated, the 100 supports or shafts D and E are preferably removably mounted, so that the wrapper-rolls may be readily placed in position.

Upon a horizontal shaft 43, revolvably mounted upon the inner ends of supports 36, is fixed a roll 44, with which co-operates a pressure-roll 45, revolvably mounted in spring-pressed boxes which slide in guideways in the supports 36. This set of feed-rolls co-operate to withdraw the wrapper-web *d'* from the roll *d*. A similar set of feed-rolls 47 and 48 is mounted upon a shaft 49, and spring-pressed bearings 50 at the outer end of the support 36 and co-operate to withdraw the inner wrapper *e'* from its roll *e*. 115

For the duplicate set of wrapping mechanisms a second pair of supports 36' are carried beside the supports 36, upon which are mounted a second set of wrapper-roll-supporting shafts D' and E' and a second set of feed-rolls 44' 45' and 47' 48', entirely similar in construction to those previously described, the shafts 43 and 49 being extended through both pairs of supports 36 and 36' and carrying, respectively, the drive-rolls 44 44' and 47 47' of the sets of feed-rolls. 120

A pulley 51 is fixed to one end of the shaft 43, and a second pulley 52 (see Fig. 4) is mounted in line therewith upon the drive-shaft B, and a drive belt or rope 53 extends 130

over these pulleys to continuously rotate the sets of feed-rolls 44 45 and 44' 45'. To the opposite ends of the shafts 43 and 49 are fixed a pair of pulleys 54 and 55, connected by a crossed belt or rope 56, by which the sets of feed-rolls 47 48 and 47' 48' for the inner wrapper-webs are continuously rotated.

To the end of the roll supports or shafts D and D' are fixed grooved brake-wheels 57, with each of which frictionally engage a brake, preferably comprising a bent weighted lever 58, pivoted to the outer upright 37 above the bearings 39 for the shaft. This brake device serves to overcome the considerable momentum of the heavy wrapper-rolls *d* if for any reason the machine is stopped and prevents the wrapper from being unwound by the continued spin of the rolls after the machine is arrested and dragging on the floor. The shafts E and E', carrying the inner wrapper-rolls E, may be provided with similar brake devices, if desired; but it has been found sufficient to provide plate-springs 59, (see Figs. 5 and 5^a), fixed at one end to the uprights 37 and having a bent free end arranged to engage the ends of the roll-supporting shaft.

The outer wrapper-web *d'* is delivered from the feed-rolls 44 45 and guided over a curved plate 60, (see Figs. 5, 7, and 8^a), fixed to a transverse bar 61, secured to the rear edge of the bed-plate A, and the inner wrapper-web *e'* from the feed-rolls 47 and 48 is guided over a plate 62, pivoted upon a transverse support 63, also secured to the rear edge of bed-plate A, but spaced somewhat to the rear of this edge and also spaced above the guide-plate 60. A roller 62^a (see Figs. 2 and 7) is preferably journaled to the plate 62 and arranged to engage the upper wrapper-web to hold it smoothly in place.

Guide-plates 61 and 62 are arranged in duplicate, as shown, for the two sets of wrapping mechanisms and deliver the wrapper-webs to duplicate sets of wrapper-guide chutes. Each of these sets comprises (see Figs. 8, 8^a, 10, and 10^a) a lower chute F for the outer wrapper mounted a slight distance above the bed-plate A between supports 64 and 65, which are secured to said bed-plate, and an upper guide-chute G for the inner wrapper mounted between these supports 64 and 65 and upon bent supporting-straps 66, the ends of which are secured to the lower chute F and by which the chute G is spaced some distance above the chute F. Each of these chutes is of sufficient width to accommodate the wrapper-web guided thereby and comprises closed bottom plates *f g* and inwardly-extending upper edges *f' g'* spaced slightly apart from the bottom plates so as to embrace the edges of and accurately guide the wrapper-webs.

The upper wrapper-chute G is bent downwardly near its inner end to join the lower

wrapper-chute F, and the common end of both chutes is formed by a short chute-section 67, which is supported between upper and lower transverse bars 68 and 69, fixed to the bed-plate A, as most clearly shown in Figs. 11 and 11^a, thus forming a common orifice or outlet for both chutes.

The lower chute-section F is provided with an opening 70, preferably arranged between the common chute-section 67 and the main body of the chute, and the upper chute-section G is provided with an opening 71, which is preferably arranged slightly in the rear of the opening 70 and between an upwardly-extending portion 72 of the common chute-section 67 and the main body of the chute G.

The chutes are arranged in duplicate, as shown in Fig. 1, and the supports 64, fixed to the bed-plate A, extend upwardly upon either side of the inner end of each pair of chutes. A horizontal shaft 73 extends across both sets of chutes, is journaled in the supports 64, and its extending ends are journaled in uprights 74. (See Figs. 10, 11, and 12.) Upon this shaft is mounted between each pair of supports 64 a pair of drive feed-rolls 75 for the outer wrapper, which project downwardly upon either side of the chute-section 67 through the opening 70 in the lower guide-chute F and into engagement with the edges of the outer wrapper therein. A pair of pressure-rolls 76, of somewhat greater width than the drive-rolls 75, coöperate with such rolls and project upwardly through an opening formed in the bed-plate A and through the opening 70 to engage the lower sides of the edges of the outer wrapper. Each pair of pressure-rolls is mounted upon a short shaft 77, which is rotatably journaled within

105
110
115
120
125
130

spring-pressed bearing-blocks 78, mounted to slide in grooves in a portion 79 of the supports 64, which project downwardly through the opening in the bed-plate A. (See Fig. 12.) Bearing-plates 80 are adjustably mounted upon downwardly-projecting stems 81, fixed to the portions 79. A guide-pin 82, fixed to the bearing-block 78, extends loosely through each plate, and a coiled cushioned spring 83 extends about the guide-pin 82 and between the bearing-block 78 and adjustable plate 80, by which means the pressure exerted by rolls 76 upon the drive-rolls 75 may be conveniently regulated.

A shaft 84 (see Figs. 1, 10, and 11) extends across both sets of chutes and is journaled in the supports 64 slightly above and in the rear of the shaft 73. Upon this shaft is mounted between each pair of drive-rolls 75 a pair of drive feed-rolls 85, which project downwardly through the opening 71 in the guide-chute G into engagement with the edges of the inner wrapper therein. Between each pair of supports 64 (see Figs. 7, 8^a, and 11^a) extends a short shaft 86, between the upper

and lower guide-chutes G and F, and upon the ends of each of the shafts 86 is mounted a pair of bell-crank levers 87, between the lower forwardly-projecting arms of which is journaled a short shaft 88, carrying a pressure-roll 89, which projects upwardly through the opening 71 in the guide-chute G and into engagement with the lower side of the inner wrapper therein and coöperates with the drive-roll 85 to feed the inner wrapper-web. A cross-bar 90 extends between the upwardly-extending members of the bell-cranks 87, to which is centrally fixed a rearwardly-projecting pin 91, extending through an opening in a cross-bar 92, which extends between each pair of supports 64. An adjusting-nut 93 is threaded on the end of the pin 91, and a cushion-spring 94 is interposed between the nut and the bar 92, whereby the pressure of roll 89 upon the coöperating pair of drive-rolls 85 may be conveniently regulated.

To accurately guide the inner wrapper to the common inner end of the chutes F and G, the upwardly-extending portion of the chute-section 67 between the openings 70 and 71 is preferably provided with a top and bottom extending from side to side of the chute-section and its top with a central finger 95, (see Fig. 7, in which the drive-rolls 85 are omitted for the sake of clearness,) which projects upwardly between the drive-rolls 85. (See Figs. 8^a and 11^a.) A drive-gear 96 for the feed-rolls (see Figs. 1, 7, and 12) is loosely mounted upon the central portion of shaft 73 and is held against longitudinal movement between a sleeve 97 and a ratchet 98, which are fixed to the shaft. A pair of spring-held pawls 99, (see Fig. 12^b), pivoted to the gear 96, engage the teeth of the ratchet 98. These pawls are preferably staggered with reference to the ratchet-teeth, so that the gear 96 will only move a slight distance in the direction of the arrow, Fig. 12^b, before one of the pawls 99 engages a tooth of the ratchet 98 and yet permitting the employment of large spring ratchet-teeth.

A longitudinal reciprocating bar 100 is mounted to slide between the folding-chutes C C' and between the two sets of paper-guide chutes F G. The rear end of the rod is provided with rack-teeth engaging the feed-roll drive-gear 96 and is guided between blocks 101, fixed to the bed-plate A. (See Figs. 7, 12, and 17.) The forward end of the rod is fixed to a cross-head 102, mounted to slide between guideways 103, fixed to the bed-plate A near and projecting beyond its forward edge. (See Figs. 1, 17, and 21.) A rubber-covered stop or buffer 103^a (see Figs. 1 and 17) is preferably mounted upon a piece connecting the outer ends of the guideways 103 and is arranged to check the outward movement of the cross-head 102 and prevent all strain upon the parts. A lever-arm 104 is pivotally mounted in a bracket

105, secured to the left-hand edge of the bed-plate A, and its free end is slotted to operatively engage the cross-head pin 106, fixed to the cross-head 102. The pivot 107 of the arm 104 is preferably formed in piece therewith and, together with the supporting sleeve or bracket 105, is of sufficient length to form a rigid bearing for the operating arm or lever 104. The lower end of the pivot 107 extends below the supporting sleeve or bracket, 75 and to its lower end is fixed a horizontally-swinging rock-arm 108, having a pin or roller 109 at its free end, which engages a cam-slot 110, formed in the under surface of a horizontal rotating cam 111, which is mounted upon 80 a vertical counter-shaft 112. This counter-shaft is mounted in upright position directly over the extending end of the drive-shaft B between a bearing 113, fixed to and extending beyond the left-hand edge of the bed-plate A and the bearing b of the drive-shaft, 85 which, as stated, is mounted upon the end bar 32 of the frame. This end bar (see Figs. 3 and 4) is bent outwardly, as shown, to properly position the bearing b beneath the end of 90 the shaft 112, and its central portion is provided with a strengthening-rib 32' to support the weight of the upright counter-shaft 112 and the parts carried thereby. The counter-shaft 112 is driven from the drive-shaft B 95 by a pair of intermeshing gears 114 and 115, fixed, respectively, to said shafts. The rack-bar 100 is thus reciprocated through the medium of the parts described and serves upon the outstroke to rotate the feed-rolls 75 for 100 the outer wrapper in the direction of the arrow (see Figs. 11^a and 12^a) through the medium of the ratchet 98 and pawls 99. The drive feed-rolls 85 for the inner wrapper are simultaneously operated (see Figs. 11 and 105 12^a) through the medium of gears 116 and 117, fixed, respectively, to the left-hand ends of the shafts 73 and 84 and operatively connected by a broad idler-gear 118, mounted upon a short stud 119, fixed to the left-hand 110 support 64.

By the intermittent operation of the feed-rolls 75 and 85, together with their coöperating pressure-rolls, the inner and outer wrappers are intermittently fed out over the bed-plate A of the machine and over the folding-chutes C C', about which the folding mechanisms are grouped. By providing the supplemental set of continuously-driven feed-rolls 115 44 45 and 47 48 slack web portions may be 120 maintained between the supplemental and main sets of feed-rolls, (see Figs. 2 and 5,) and the main set of intermittently-operated feed-rolls need only operate upon a short portion of the wrapper-webs. The drag upon 125 the paper wrapper-web which is often quite weak is therefore very slight, and the chutes G and F may be interposed to accurately guide the webs to the folding mechanism. Moreover, the wrapper-rolls are of consider- 130

able weight, and if the web were withdrawn therefrom directly by the main set of intermittently-actuated feed-rolls it would be necessary to successively start and stop the heavy paper-rolls D and E, and it is entirely inexpedient to do this with any degree of speed. Therefore by interposing the supplemental continuously-driven set of feed-rolls which continuously withdraw the wrapper-webs from their rolls the speed of the machine is materially increased.

The cross-bars 69, upon which the common inner ends of the duplicate sets of wrapper-guide chutes F and G rest, are projected inwardly a slight extent (see Figs. 11^a and 14^b) and are formed with upper inner cutting edges f''.

Opposite each outer side of the folding-chutes C and C' is mounted upon the bed-plate A a pair of uprights or standards 120, connected by the top and intermediate cross-bars 121 and 122. (See Figs. 3, 4, and 15.) A pair of brackets 123 (see Figs. 2 and 16) is mounted upon the top cross-bar 121 and have rearwardly-projecting horizontal studs 124, to the ends of each of which is pivoted to swing transversely in a vertical plane an arm 125. (See Figs. 14, 15, and 16.) A block or cross-head 126, sliding longitudinally between guides 127, fixed to the outer free end of each of the arms 125, carries upon its projecting lower end a short stud-shaft 128, whereon is fixed a rotatable cutter F'. The knives F' by transverse movement coöperate with the cutting edge f'' to sever the separate wrappers from the continuous web and are guided in a straight line during such movement by a beveled abutment or guide 129, carried above and in front of the cutting edges f'', but parallel therewith, upon a pair of supports 130, fixed to the bed-plate A. An annular beveled abutment 131, to which the cutter F' is fixed, is yieldingly pressed on to frictional rolling contact with the beveled guide 129 by a cushion-spring 132, mounted between lugs fixed, respectively, to the swinging arm 125 and the sliding block 126 and guided upon a pin 133, fixed to one of said abutments and sliding loosely through the other. The beveled abutment 131 and guide 129 are inclined downward, as shown, toward the cutting edge f'', and since the abutment 131 is downwardly pressed by the spring connections 132 these bevels coöperate to force the cutting periphery of the knife F', which extends slightly past the cutting edge f'', closely against said cutting edge. Moreover, since the abutment 131 is of smaller diameter than the circular knife F' the cutting periphery will have a relatively greater velocity, and consequently sever the wrapper-web with a positive shearing action. The knives are prevented from riding upwardly by a second guide-bar 134, mounted between the upper ends of the supports 130

and with the lower edge of which engage anti-friction-rollers 135, rotatably mounted upon rearwardly-projecting portions of the studs 128. The swinging arms 125 are connected by a link 136 and are reciprocated by a pivoted lever 137, the upper free end of which extends upwardly through an opening in the bed-plate A and is connected to one of said arms by a link 138. The links 136 and 138 are preferably formed of two parts adjustably secured together by a suitable connector 139, by which the throw of the arms 125 may be adjusted.

The lower end of the operating-lever 137 is pivoted in a bracket 140, secured to one of the cross-bars 33, (see Figs. 4 and 16,) and a pin or roller 141 operatively engages a suitably-shaped cam-groove 142 in the front face of a rotating cam 142'. The outer end of the pin 141 is preferably braced by a bent bar 143, extending between said end and the pivoted end of the lever 137. The cam 142 is mounted upon a horizontal counter-shaft 144, which is journaled in bearings 145, fixed to the cross-bars 33, and is driven from the main drive-shaft B by the intermeshing pair of beveled gears 146. The rear outer end of this counter-shaft is preferably braced and journaled in the end of a brace-rod 147, connected to one of the legs or uprights 30 of the main frame.

Upon a pair of short parallel links 148, pivoted to the rear sides of the supports 130, is mounted a clamping member or rod G' above the bars 69, whereon the cutting edges f'' are formed. This clamping member or rod is normally upheld above the bars 69 (see Fig. 15) and above the inner open ends of the paper-guide chutes by a pin 149 upon the knife-operating lever 137, which engages a slot 150 in a link 150', pivoted to one end of the rod G'. As soon, however, as the lever 137 commences its throw to reciprocate the cutting-knives (see Fig. 15^a) a spring 151, extending between an abutment 152 and an abutment 153, mounted, respectively, upon the clamping-bar G' and a fixed upright 154, operates to move the clamping member downwardly between the cutting member F' and the inner open ends of the wrapper-guide chutes to clamp the wrapper-webs firmly against the transverse bars 69 and prevent them from being wrinkled during the cutting operation. The lug 153 is preferably adjustably mounted (see Fig. 15^a) in the upright 154, by which the tension of the clamping-rod spring 151 may be adjusted. With this peculiar form of rotatable reciprocating knife F' and clamping member G' the wrapper-webs, which are often of very delicate material, will be accurately and neatly cut and not crushed or moved out of position. The main set of feed-rolls for the wrapper-web and cutting-knives are of course operated alternately to feed the separate wrap-

pers to the folding mechanism and sever them from the web.

A transverse guide-grip plate H, (see Figs. 2, 17-18^b), of a width sufficient to extend across both of the inner open ends of the duplicate sets of wrapper-guide chutes F and G, is centrally fixed upon the rack-bar 100 intermediate its ends. The grip-plate H reciprocates with the rack-bar 100, its ends being guided in ways 155, longitudinally fixed to the upper face of the bed-plate outside of the folding-chute openings a a'. Upon opposite sides of the rack-bar are hinged a pair of transverse spring-pressed plates or jaws h of sufficient width to engage the outer wrapper d' and provided with a downwardly-turned inner gripping edge 156. Each of the plates or jaws h is provided near its ends with a downwardly-projecting semicircular abutment 157 and projects through an opening in the plate H, which at the end of the forward stroke of the guide-grip engages beveled cams 158, fixed to the upper face of bed-plate A and serving to open the guide-grip to receive the inner projecting edge of the wrapper-web. A second spring-held grip plate or jaw h' of sufficient width to engage the end of the inner wrapper is pivoted to the plate H within a central cut-away portion of each of the grip plates or jaws h, being preferably mounted on the same pivot-rod therewith. The forward edge of each of the grip plates or jaws h' is provided with a downwardly-turned gripping edge 159, and oppositely-extending lugs 160 are fixed to the upper face of each of said plates and project into engagement with the grips or jaws h, so as to be lifted or opened with the latter to receive the inner free edge of the wrapper-webs when the abutments 157 engage the fixed cams 158. The gripping edge 156 of the plates H is cut away (see Fig. 18^a) in front of the gripping edges 159 of the plates h'.

As clearly shown in Fig. 17, the operating-cam 111 for the rack-bar 100 and guide-grip H has a cam-groove 110, the portion of which nearest the center of the cam is concentric to provide a short dwell, so that the guide-grip H (see Fig. 28) will be moved inwardly adjacent the cutting edge f'', opened, and held stationary for a brief period. In order that the guide-grip may engage the forward inner edge of the wrapper-webs, which is of course cut off even with the cutting edge f'', the feed-rolls 75 and 85 are given a slight preliminary or advance feed. For this purpose a ratchet-wheel 161 (see Figs. 11, 12, 12^c, and 12^d) is mounted upon the right-hand end of the shaft 73 near its outer end bearing 74, and between the ratchet and adjacent bearing is loosely mounted an arm 162, carrying a pair of spring-pressed pawls 162', which are staggered, as shown, so that only a slight movement of the arm 162 can take place before one of the pawls 162' will engage the

ratchet-wheel 161, and yet permitting the use of large heavy ratchet-teeth. An operating-lever 163 is pivoted at its lower end upon a short rock-shaft 164 to swing toward the front and rear of the machine and projects upwardly through an opening in the bed-plate A. A link 165 is pivotally connected to the upper free end of the operating-lever (see Fig. 16) and adjustably and pivotally connected to the arm 162 by a bolt 166, engaging a slot 75 therein: The shaft 164 (see Fig. 4) is suitably journaled in a bracket 167, mounted upon one of the cross-bars 33 and in the end piece 32, and the outer end of the shaft is provided with a rock-arm 168, having a pin or friction-roller at its inner end engaging a suitably-shaped cam-slot 169 in the outer face of a rotating cam 169', (see Fig. 16,) mounted upon the drive-shaft B. A portion of the slot is designed to move the upper end of operating-arm 163 toward the rear during the dwell described of guide-grip H, and thus, through the medium of the pawl-and-ratchet connection described, give the feed-rolls 75 and 85 a slight preliminary or advance feed in the direction of the arrows in Figs. 12^a and 12^b, so as to move the forward inner edges of the wrappers within the open jaws, as indicated in Figs. 18 and 28.

As the rack-bar 100 moves toward the front the abutments 157 on grip-plate h are disengaged from the inclined cams 158, and the grip-plates h and h' descend into engagement with and grasp the forward edges of the wrapper-webs, and the feed-rolls 75 and 85 are operated simultaneously with the guide-grip H to feed the inner and outer wrappers into position over the folding boxes or chutes C C'. The grip H merely serves not to pull the paper forward, (since this is inexpedient with any but a very stout wrapper,) but solely to guide the forward edges of the wrapper-web accurately and free from wrinkles into position. The pitch-circle of the drive-pinion 96, with which the rack-bar 100 co-operates to drive the feed-rolls 75 and 85, is of substantially the same or slightly larger diameter as that of the drive-rolls 75, so that the outer wrapper d' is fed positively by the roll 75 at substantially the same or a little less speed than the guide-grip H.

The gripping pressure on the grip-plates H and H' is very light, so that the wrappers as they are fed forward may be withdrawn slightly therefrom, the object of the guide-grip, as before stated, being solely to stretch the paper smoothly in accurate position over the folding chutes.

The pinion 117 (see Fig. 12^a) upon the shaft 84 of the feed-rolls 85 for the inner wrapper is slightly smaller than the corresponding pinion 116 upon the shaft 73 of the feed-rolls 75 for the outer wrapper. Moreover, the feed-rolls 85 themselves are preferably slightly smaller than the feed-rolls 75, the parts be-

ing so proportioned that the inner wrapper *e'* will be fed at a slightly less speed than that of the outer wrapper *d'*, and at the end of the complete forward stroke of the guide-grip *H* its forward edge will be withdrawn slightly therefrom and will be spaced short of the forward edge of the outer wrapper, as indicated in Fig. 28^b, so that in the complete folded package the inner wrapper will not project in an unneat manner.

Upon the end of the drive-shaft 73 for the wrapper-feed rolls opposite the advance feed-arm 162 is fixed a brake-wheel 170, (see Figs. 12, 13, and 13^a), which projects downwardly through an opening in the top of bed-plate A. A brake-shoe 171 for engaging the wheel is pivotally mounted beneath the bed-plate A upon the upper short arm of a bell-crank lever 172, which is pivotally mounted between lugs 173 upon the under side of the bed-plate. The lower downwardly-extending arm of the bell-crank carries a piece 174, which is adjustably connected thereto by a screw 175 (shown in detail in Fig. 13^b) and which carries a roller 176, adapted to be engaged by a pair of cam-lugs 177 and 178, spaced apart and adjustably secured by bolt-and-slot connections to the face of a cam 179 (see Figs. 4, 13, and 13^a) upon the main drive-shaft B. These cam-lugs 177 and 178 are so positioned as to throw the brake into operation at the end of the advance feed for the wrapper-feed rolls by the arm 162 and also at the end of the main feed for these rolls by the rack-bar 100, thus arresting the momentum of the feed-rolls 75 and 85 after they have operated to feed a sufficient length of the webs to form a single set of inner and outer wrappers, and so also the cutting-knives F will sever the web between the separate printed portions thereon. This brake-stopping device will operate for several times in succession to arrest the travel of the wrapper-web in proper position, so that the knife will sever it between separate printed sections and so that the fanciful or other advertising matter thereon will register accurately with the soap cakes or other articles; but the wrapper-rolls frequently contain several thousand printed sections arranged end to end upon the continuous web, so that any slight variation either in the operation of the brake or of the feed-rolls or and any slight variations in the lengths of the separate printed sections will be finally multiplied until the wrapper-web would be arrested in such position that the knife would cut into the printed sections of the wrapper and the printed portion would no longer register accurately with the articles. It may be noted that the wrappers necessarily vary in length from day to day in accordance with the atmospheric conditions and in accordance to the extent to which they have been dried after they have been printed, and no uni-

formly - operating mechanism can be depended upon to sever the separate printed portions from the web. For these reasons a separate correcting stop device is attached to positively engage and check the forward travel of the wrapper-webs, which is controlled by the lengths of the separate printed sections and which is independent of the variations of such lengths and of the feed for the wrapper-web.

At the rear and upon opposite sides of each of the sets of wrapper-guide chutes F and G are mounted upon the table A the uprights or supports 65, (see Figs. 2, 7, 8, 8^a, and 9,) connected at their upper ends by a cross-bar 180 and at their lower ends by the clamping-plates 181 and 182, which are arranged, respectively, in alinement with the bottoms of the guide-chutes F and G. Above the clamping-plates 181 and 182 are journaled between the supports 65 a pair of rock-shafts 183 and 184, each of which is provided with rearwardly and downwardly inclined rock-arms 185, carrying between their free ends the clamps 186, which are preferably covered with rubber or other suitable material and arranged to transversely engage and arrest the forward travel of the wrapper-webs *d'* and *e'*, the respective clamps for the inner and outer wrappers being of a width to correspond thereto. Each of the rock-shafts 183 and 184 is provided with a pair of forwardly-extending rock-arms 187, to the outer free ends of which are connected the actuating-springs 188. The upper ends of these springs are connected to rods 189, which extend through the top cross-bar 180 and provided with thumb-pieces 190 and adjusting-nuts 191. By this means proper tension may be placed upon the actuating-spring 188 to firmly grip the wrapper-webs despite the slight continued movement of the feed-rolls 75 and 85.

The ends of the shafts 183 and 184 project out beyond the supports 65 and are provided with rearwardly-projecting rock-arms 192, the free ends of which are connected by links 193, and the extreme outer ends of each of the shafts 184 are journaled in an upright 195 on the bed-plate A and provided with forwardly-extending arms 196, (see Figs. 1, 7, and 8,) each arranged to engage a vertical latch *j*, so as to normally hold each set of stop-clamps out of engagement with the wrapper-webs. Each of the latches *j* is pivoted to a plate 197, arranged outside of the wrapper-guide chutes, and is normally held into engagement with the arm 196 and against a stop-rod 198 by a spring 199, extending between the latch and a short rod 200. The stop-rod 198 and the rod 200 are mounted on an upright 200' and each provided with thumb-pieces 201 and adjusting-nuts 202, as clearly shown in Fig. 8.

An electromagnet J is mounted in horizon-

tal position above each of the plates 197 upon a standard 203 and arranged with its poles opposite the adjacent latch *j*, to each of which is fixed an armature 204 for the adjacent magnet *J*. In the energizing-circuit of each of the magnets *J* is interposed a circuit-closer mounted upon a support 205, (see Figs. 1, 7, 9^a, 9^b, and 9^c,) fixed to the bed-plate *A* upon one side of the lower wrapper-guide chute *F*. A block 206, mounted to slide in guideways in each of the supports 205, carries upper and lower projecting portions 207 and 208, which extend laterally above and below the lower paper-guide chute, as clearly indicated in Fig. 9^c. To the upper portion is pivoted intermediate its ends a contact-finger 209, which carries at one end a contact-roller 210, which projects downwardly through an opening in the wrapper-guide chute *F* normally into engagement with the edge of the wrapper-web *d'* therein. The lower projecting portion 208 carries a similar roller 211 directly beneath the roller 210, which projects upwardly through an opening in the wrapper-guide chute and normally engages the lower side of the wrapper-web *d'*. The finger 209 is pivoted upon a suitable insulating-sleeve or otherwise insulated from the body of the machine, and a spring 212 is connected to its rearwardly-extending end and to a short rod 213, mounted in a piece of insulating material 214 and provided with an adjusting thumb-nut 215, by which spring its contact-roller 210 is pressed downwardly against the contact-roller 211.

The lower wrapper-web *d'* is provided with openings in its edge (see Fig. 10) opposite each of the separate printed wrapper-sections thereon, which are preferably punched in the web just as it leaves the printing-press, so that the distance between the holes will exactly correspond to the lengths of the printed sections. The contact-finger 209 and rollers 210 and 211 are mounted in line with these openings, and when the web has traveled a sufficient distance to bring one of the openings between the rollers contact is made, and the circuit may then be traced (see diagrammatic Fig. 9^d) from a battery 216, by wire 217 and by a short lead 218, to the magnet *J*, from thence by a lead 219 to a binding-post 220 upon a piece of insulating material 221, fixed to the support 205, from thence by a short wire 222 to the insulated contact-finger 209, and from thence by contact-roller 211 and through the metal of the machine to the shaft 144. Upon this shaft is mounted a commutator 223, (see Figs. 21 and 21^b,) having a short metal contact 224, which is arranged to engage at the proper moment with a brush 225, of spring metal, which is mounted upon but insulated from one of the cross-bars 33 and which is connected to the return battery-wire 226. The commutator 223 is arranged to close the

battery-circuit just before one of the openings in the wrapper-web reaches the contact-finger 209, (thus avoiding the accidental operation of the magnets except at the proper point and saving the strength of the battery,) and when the circuit is completed by the latter through the opening in the wrapper-web, the magnet *J*, controlled by the finger, will be energized, withdraw the latch *j* from engagement with the rock-arm 196, and the set of stop-clamps 186 are forced by their actuating-springs 188 into engagement with the wrapper-webs *d'* and *e'* to arrest the forward travel. As clearly indicated in Fig. 9, the two sets of stop-clamps for the two sets of folding mechanisms are entirely independent of each other and are also independent of the feed-rolls, so that the forward travel of either of the sets of wrapper-webs will be immediately arrested as soon as the opening in the edge of the lower web permits contact to be made by the corresponding finger 209. By this means the forward travel of the wrapper-webs will be arrested at such point that the separate wrappers will always register exactly with the articles to be wrapped and the cutting-knives *F'* will always sever the webs between the separate printed sections, since the operation of this correcting stop device is controlled solely by the forward movement of the web and is independent of any variations in the feed of rolls 75 and 85 and of any variations in the lengths of the separate wrappers. It will be seen that this mechanism, which is controlled by the movement of the wrapper-web, serves to properly time the movement of the wrapper-web relatively to the operation of the cutter, so that the separate printed sections of the web are properly and successively severed therefrom.

The tension of the actuating-springs 188 is sufficient to render the grip of the correcting stop devices upon the wrapper-webs greater than that of the feed-rolls 75 and 85 and their coöperating pressure-rolls 76 and 89, so that any further slight movement of the feed-rolls after the correcting stop-grips have been thrown into operation will be entirely ineffectual to feed the wrapper-webs; but the brake 171 is arranged to engage the brake-wheel 170 (see Figs. 12 and 13) upon the drive-shaft 73 about the time that the correcting stop-grips are operated, so that the momentum of the feed-rolls is overcome and any unnecessary drag or strain upon the webs avoided.

An adjusting-stud 227 is threaded into one end of the block 206, which carries the contact-rollers 210 and 211, and the outer end of the rod 227 (see Figs. 9^a and 9^b) is provided with a thumb-piece and swiveled in a projection 228, fixed to the support 205. By this means the position of the circuit-closer may be adjusted and the actuation of the

correcting stop-grips accurately timed to arrest the forward travel of the wrapper-webs at the correct moment.

Extending across both sets of stop-grips 5 and journaled in the supports 65 is a rock-shaft 229, (see Figs. 8, 9, and 16,) the outer extending ends of which are journaled in the uprights 195 and provided with eccentrics or cams 230, positioned above the rock-arms 196. To one end of the shaft 229 is fixed a crank-arm 231, connected by a link 232 to the upright lever 163, so that upon the forward movement of the latter the arms 196 are depressed by the cams or eccentrics 230 15 to release the correcting stop-grips and permit the forward feed of the wrapper-webs. The circuit through the magnets J is then broken, both by the intervention of the wrapper-web between the contact-rollers 210 and 211 and by the movement of the commutator 223 upon the shaft 144, so that the latches j are pulled back by their springs 199 against their stops 198, and the complete downward movement of the cams or eccentrics 230 depresses the arms 196 into reengagement with the latches. The backward movement of the pivoted lever 163 lifts the cams or eccentrics clear of the arms 196, so that when the latches j are tripped the stop-grips 186 are free to be thrown suddenly into engagement with the wrapper-webs by their actuating-springs 188.

A chute or feedway K for the articles to be wrapped, having closed bottom and side walls, 35 (see Figs. 1, 19, and 20,) is horizontally positioned a slight distance above the bed-plate A and projects considerably to the left-hand side of the machine, as shown, its outer end being suitably supported by uprights 233. The inner end is positioned in front of the openings a a' in the bed-plate A and mounted upon a raised support 234, fixed to the table A and extending above the wrapper-grip H and the guideways 155 therefor. 40 (See Fig. 28^b.) An endless feed-belt k travels over a guide-pulley 235, journaled at the outer end of the feedway or chute K, over the bottom of the chute, and over a drive-pulley 236, and downwardly and horizontally over 45 a pair of guide-rolls 237, fixed to cross-bars 35 and 33, back to the guide-pulley 235.

Drive-wheel 236 for the belt is mounted on horizontal counter-shaft 238, (see Figs. 4, 20, and 21,) which is journaled between uprights or standards 239, mounted upon the cross-bars 35. A gear-pinion 240, loosely mounted on the rear end of the counter-shaft 238, carries a pivoted spring-pressed pawl 241, engaging the teeth of a ratchet-wheel 242, fixed to the shaft, for intermittently rotating the drive-wheel and feed-belt in the direction of the arrow, Fig. 20. The loose gear-pinion 240 is oscillated by a gear-segment 245, pivoted at its lower end and connected by an eccentric-strap 246 and rod 247

to an eccentric 248, mounted upon the rear end of the counter-shaft 144. The end of the eccentric-rod 247 is connected to the gear-segment 245 by a pin 249, engaging a vertical slot therein, by which the intermittent throw of the feed-belt k may be adjusted.

The articles L are fed into the extending end of the feedway K either automatically or by hand, are arranged endwise therein, as indicated by dotted lines in Fig. 19, and are fed by the movement of the belt k against a vertically-disposed stop-plate 250, extending across the end of the feed way or chute, but above the belt k between the support 234, and a vertically-disposed cross-plate 251, 80 which is secured at either end to the uprights 120 upon the bed-plate A. (See Fig. 15.) This cross-plate 251 is positioned, as indicated in Fig. 28, at the same level with the feed-chute K and above the path of movement of 85 the wrapper-guide grip H.

The front wall of the feedway K is provided with openings opposite the folding boxes or chutes C C', through which may be projected a pair of horizontally-reciprocating 90 plungers M M', having operating-rods m m', each of which is guided at its inner end between a roller 252 and a clamp-piece 253, fixed upon the upper face of the support 234, and at its outer end in a bearing 254. The rods m m' are connected by a cross-head 255, which is centrally provided with a pin 256, arranged to engage a slot in the inner free end of a horizontally-disposed operating-lever 257. The outer end of the lever 257 is 100 fixed to the upper end of a short vertically-disposed rock-shaft 258, which is journaled (see Fig. 21^a) within a central bore formed in the pivot 107, which in turn, as previously described, is journaled in the sleeve or 105 bracket 105. To the lower end of the shaft 258 is fixed an arm 259, the inner free end of which is provided with a pin or roller 260, engaging a cam-slot 261, formed in the upper face of a cam 262, which is fixed upon the 110 vertically-disposed counter-shaft 112.

The stop-plate 250 and the plungers M M' are so positioned that when the latter move inwardly through the feed-chute K and over the belt k two of the articles (in this instance 115 the first and fourth) will be projected through oppositely-arranged openings in the rear wall of the feed way or chute K, each into the grasp of a pair of clamping-plates N. After the withdrawal or outward movement of the 120 plungers M M' the movement of the belt k will feed the articles forward again against the stop-plate 250, filling up the spaces formed by the ejection of two of the articles by the plungers. In the present instance 125 the plungers and feed-belt are alternately operated; but, if desired, the feed-belt may be continuously operated without interfering with the regular feed of the articles into the clasp of the clamping-plates N. These 130

clamping-plates are fixed to vertically-disposed cross-plates 263, which are mounted between the rear side wall of the feed-chute K and the cross-plate 251 in such position 5 that the articles are held by clamping-plates N directly above the folding-chutes C C' and above the wrappers, which are fed over the chutes, as indicated in Fig. 28^b. The clamping-plates N are preferably of spring metal, 10 and the opposite plates of each pair are bent inwardly toward each other to guide the articles accurately to position and to grip the articles with sufficient pressure to hold them in position over the folding-chutes C C' and 15 to prevent their return with the return movement of the feed-plungers M M'.

A pair of vertically-reciprocating plungers O O' (see Figs. 2 and 3) are mounted directly above the folding-chutes C C' between the 20 standards 120 and their operating-rods o o' and are guided at their lower ends in opening formed in the cross-bar 122. The upper ends of the rods o o' are connected by a cross-head 264, which is provided with a central 25 vertical guide-pin 265, sliding through an opening in the cross-bar 121, and which is also provided with a rearwardly-projecting pin 266, arranged to engage a slot in the end of an operating-lever 267. The latter lever 30 is centrally pivoted to the rear side of the right-hand upright 120, and to its outer free end is connected a link 268, which extends downwardly through an opening in the bed-plate A and connects with an upper laterally-projecting arm of a bell-crank 269. (See 35 Figs. 3 and 4.) The bell-crank 269 is pivotally mounted upon a bracket 270, fixed to the under side of bed-plate A, and its lower downwardly-extending arm is provided at 40 its free end with a pin or roller 271, which engages a circumferential cam-groove 272, formed in the periphery of the cylindrical cam 179, fixed to the main drive-shaft B. A weight 273 for balancing the weight of the 45 plungers O O' is preferably fixed upon the vertical connecting-link 268. As soon as the outer and inner wrappers d' and e' are moved into position over the folding-chute and the article L has been projected into the grasp of 50 the plates N the plungers O O' descend and force the articles, together with the inner and outer wrappers, into the folding chutes or holders C C', as indicated in Fig. 28^c. Each of these chutes (see Figs. 22, 23^b, inclusive) 55 is mounted upon a bracket 274 and a bracket 275, which are fixed to the under side of the bed-plate A at the front and rear, respectively, of the openings a a'. The lower ends of the brackets are connected at one end by 60 the cross-pieces 276 and 277 (see Fig. 23^a) and at the other end by a cross-piece 278. (See Fig. 23^b.) The front wall of the chute is formed in piece with the bracket 274 (see Fig. 22^a) and projects upwardly through the 65 opening a even with the top of the bed-plate A.

The rear wall of the chute is formed by a plate 279, extending upwardly through the opening a even with the upper surface of the bed-plate A, and pivoted at its lower end between the cone-shaped ends of a pair of bearing-studs 280 and 281, threaded, respectively, through the end cross-bars 276 and 278. These bearing-studs are preferably provided, as shown, with lock-nuts 282. A plate 283, of spring metal, is fixed to the upper inner edge of the 75 plate 279 and extends downwardly within the chute. The plates 279 and 283 are held in position by a pin 284, fixed to the former, projecting through the wall of bracket 275 and provided at its rear end with an adjustable thumb-nut 285. A cushion-spring 286 is interposed between the bracket 275 and the plate 279 and extends about the pin 284. By this means a rear pressure-wall for the chute is provided which will yieldingly and evenly 80 engage the packages in the chute (see Fig. 28) and firmly and gently hold the same in position during the wrapping operations. A pressure-wall of this sort will exert an even pressure both at the upper and lower ends of 85 the chute and yet is so mounted that it is always free to yield readily, and there is no danger that it will be cramped in position, so as to injure the articles that are forced into the chute. The cross-piece 278 forms a fixed 90 side wall for the chute, and its upper edge is positioned at a distance below the upper face of table A equal to the thickness of one of the packages (see Fig. 28^a) and is provided with a projecting ledge or abutment 287. The opposite side wall is yieldingly supported and is constructed similar to the rear pressure-wall of the chute. As shown, it comprises a plate 289, terminating at its upper end at a level with the opposite side wall 278 and 95 pivoted at its lower end between bearing-studs 290, adjustably threaded through the bracket 275, and a piece 291, fixed to the bracket 274. A spring pressure-plate 292 is fixed at its upper edge to the upper edge of 100 the plate 289 and extends downwardly within the chute. This pressure-wall is held in position by a pin 284, adjusting thumb-nut 285, and spring 286, similar to that described for the rear pressure-wall, and extending between the plate 289 and the cross-bar 276. To the upper edge of the side pressure-wall is hinged or pivoted a plate or abutment 293, 105 guided in right-line direction by a pin 294, extending loosely through a bent plate 295, 110 which is fixed to the cross-bar 276. To the upper edge of the side pressure-wall is hinged or pivoted a plate or abutment 293, 115 guided in right-line direction by a pin 294, extending loosely through a bent plate 295, 120 which is fixed to the cross-bar 276.

A pair of rear top or side folders P P', (see Figs. 2, 17, and 25,) consisting of flat plate-sections having rounded edges, are mounted to slide upon the upper face of the bed-plate 125 A between guides 296 and below the wrapper-feed mechanism on the bed-plate. These top or side folders are provided with rearwardly-projecting stems 297, mounted to slide between guide-blocks 298, fixed to the upper 130

face of bed-plate A. A similar pair of front top or side folders Q Q' are mounted to slide upon the upper face of the bed-plate and are provided with forwardly-projecting guide-stems 299, mounted to slide between guide-blocks 300. Beneath the table (see Figs. 2, 24, and 25) are mounted to slide in guide-ways 301 a pair of cross-heads 302 and 303, each of which is provided with a pair of openings 304. A pair of pins 305, fixed, respectively, to the pairs of rear and front side folders P P' and Q Q', project downwardly through slots 306 in bed-plate A and through openings 304 in the cross-heads 302 and 303. The openings 304 and slots 306 are preferably extended slightly in a direction at right angles to the direction of movement of the parts, or, in other words, are of greater width than the diameter of the pins 305 to permit a slight amount of play in that direction and to prevent the parts from binding.

The cross-heads 302 and 303 are connected by short links 307 to the upwardly-projecting arms of a pair of bell-cranks 308 and 309, which are pivotally mounted upon standards or uprights 310, fixed to the cross-bars 34. (See Figs. 4 and 25.) The lower forwardly-projecting arm of the bell-crank 308 is provided at its free end with a pin or roller 311, engaging a cam-slot 312, formed in the right-hand face of a cam 313, centrally fixed upon the main drive-shaft B. The lower rearwardly-projecting arm of the bell-crank 309 is provided at its free end with a pin 314, engaging a cam-slot 315, formed in the left-hand face of cam 313.

The rear folders P P' are normally positioned with their forward edges in line with the rear edges of the folding-chutes C C', and the front side-folders Q Q' are normally positioned with their rear edges in line with the front edge of the folding-chutes. As soon, however, as the article L together with its wrappers d' and e' have been projected by the plungers O O' within the chutes, the rear side-folders P P' are projected forwardly (see Fig. 28^d), and fold down the rear side-flap of the wrapper. The rear side-folders are then withdrawn and the front side-folders Q Q' projected to fold down the front wrapper-flap. (See Figs. 28^e and 28.) The cam-slot 312 in the cam 313 for operating the rear side-folders (see Fig. 25) is of such an outline that these side-folders are projected rapidly forward and withdrawn at once. The cam-slot, however, for operating the front side-folders is so formed that these folders will be projected rearwardly to hold the wrapper in place while the ends of the wrappers are being folded.

The pairs of rods 316 and 317 (see Fig. 3) are mounted to slide through the cross-bars 121 and 122 upon either side of the plungers O O' and carry on their lower ends the pairs of end-tuckers R R', which consist of flat

plates having rounded outwardly-turned lower edges for engaging the end portions of the wrapper. These end-tuckers are normally spaced above the top plate A (see Figs. 3 and 28^e) and between the grip-plates N and the supporting-plates 263 therefor. These latter are preferably outwardly bent, as shown, (see Fig. 19,) to form a space through which the end-tuckers may move. The upper ends of the supporting-rods 316 and 317 are connected by a cross-head 318, which is provided with a central pin 319, engaging a slot in an operating-lever 320. The latter lever is centrally pivoted intermediate its ends to the front side of the right-hand upright 120, and its outer free end is connected to the upper end of a vertical rod or link 321, which extends downwardly through an opening in the bed-plate A and is connected to the outer end of the upper laterally-extending arm of a bell-crank 322. This bell-crank is pivotally mounted to the forward side of the bracket 270, and the free end of its lower downwardly-extending arm is provided with a pin or roller 323, which engages a peripheral cam-groove 324, cut in the surface of the cylindrical cam 179. A weight 325 is preferably fixed upon the rod 321 to balance the weight of the end-tuckers.

The rods 316 and 317 for the end-tuckers, which are fixed to the cross heads 318, are in line with the operating-rods o o' for the plungers O O', and with the guide-pin 265, which are fixed to the cross-head 264. (See Fig. 3^a.) In order that these cross-heads may slide past one another, the end-tucker cross-head 318 is provided with rearwardly-projecting studs for engaging the rods 316 and 317, and the plunger cross-head 264 is provided with forwardly-projecting studs for engaging the rods o o' and the guide-pin 265.

As soon as the front side-folders Q Q' have been projected over the package the pairs of end-tuckers R R' are projected downwardly through openings 326 in the folders Q Q' (see Fig. 17) to form the top end fold, as indicated in Fig. 28. It will be noted that the wrapper-guide grip H (see Figs. 28^e and 28) is rearwardly moved simultaneously with the front side-folders Q Q' and that the end-tuckers R R' project downwardly in front of the guide-grip H. As soon as the end-tuckers R R' move back to normal position the grip H moves forwardly, guiding the front edge of the outer and inner wrappers d and e' into position. (See Fig. 28^a.)

Between the lower ends of the pair of brackets 327, (see Figs. 2, 26, and 27,) fixed to the under side of the bed-plate A in the rear of the folding-chutes, is mounted a shaft 328, which carries an upwardly-projecting pair of actuating rock-arms 329. A cross-bar 330 is pivotally mounted between the free ends of the rock-arms 329 and carries a rearwardly-extending arm 331. The rear

end of the arm 331 is pivoted to the upper end of a guiding rock-arm 332, which is parallel with and of the same length as the rock-arms 329 and pivoted at its lower end upon a bracket 333, fixed to the under side of the bed-plate A. Pairs of supporting-arms 334 and 335 are fixed to the upper face of the transverse bar 330 and carry upon opposite sides of each of the folding-chutes C C' the pairs of rear side end-folders S S'. Each of these end-folders comprises a side portion 336, a bottom portion 337 at right angles to the side portion 336, and an inclined end portion 338.

15 The front side end-folders T T', of similar construction to the rear side end-folders S S', except that they are faced in the opposite direction, are similarly mounted upon rearwardly-projecting supports 339, fixed to the upper face of a transverse bar 340, which is pivotally mounted between upwardly-extending actuating rock-arms 341. Rock-arms 341 are pivoted upon a transverse rock-shaft 342, which is journaled between brackets 343, which are secured to the lower face of the bed-plate in front of the folding-chutes C C'. A forwardly-projecting arm 344 upon the bar 340 is pivoted at its forward end to the upper end of a guiding-rock arm 345, which is parallel to and of the same length as the rock-arms 341 and which is pivoted at its lower end to a bracket 346, secured to the lower face of the bed-plate A. To the left-hand end of the rock-shaft 328 is fixed an arm 347, having a pin or roller 348 at its free end, which engages a suitably-shaped cam-groove 349, cut in the left-hand face of a cam 350, (see Figs. 4 and 27,) mounted upon the main drive-shaft B, by which the rear side end-folders S S' are operated. The shaft 342 carries at its left-hand end a rock-arm 351, the outer free end of which is provided with a pin or roller 352, which engages a cam-slot 353, formed in the right-hand face of the cam 350, by which the front end-folders are operated. The parallel movement described imparts a rocking motion to the end-folders S S' and T T', but at the same time always maintains the end-folders in horizontal position.

50 The pairs of front and rear side end-folders S S' and T T' normally project upwardly within slots 353, formed in the bed-plate A, at the opposite ends of the openings a a', with their ends in line with the front and rear side walls of the chutes. (See Fig. 28c.) As soon, however, as the end-tuckers R R' have moved downwardly the operating cam-slots 349 and 353 of the cam 350 are so shaped that both the front and rear side end-folders are projected inwardly to a slight extent (see dotted lines in Fig. 28) to hold the end fold after the end-tuckers R R' have been withdrawn. The front end-folders T T' are then moved inwardly and downwardly against the

end tables 287 and 293 of the side walls of the 65 chutes by the parallel movement described, drawing the wrappers smoothly and firmly around the front edges of the packages and creasing the front end fold against the tables. (See Fig. 28a.) The front side end-folders T 70 T' are then withdrawn and the rear side end-folders S S' similarly projected inwardly and downwardly against the tables 287 and 293 (see Figs. 3 and 28b) to draw the wrappers firmly around the rear edges of the packages 75 and to crease the rear end-fold against the tables. By the peculiar construction and operation of these end-folders the end folds of the packages are so creased that the wrapper will not become unfolded when the packages 80 are removed from the boxes in which they are contained.

While the end folds are being completed by the folders S S' and T T' the feed-rolls 75 and 85, cutters F', and guide-grip H have 85 been operated to bring another set of wrappers into position over the chutes C C' and the plungers M M' have been operated to project two more packages within the grasp of the plates N N over the folding-chutes, 90 as shown in Fig. 28b. As soon as the rear end-folders S are withdrawn the vertically-reciprocating plungers O O' descend and project the second set of packages or articles, together with their wrappers, into the 95 chutes, thus forcing the previous package in the upper end of the chute downwardly past the side walls of the chutes and completing the end fold. (See Fig. 28c.)

A pair of delivery-chutes U U' are positioned beneath the lower open ends of the folding-chutes C C' in position to receive the completed packages as they are finally ejected therefrom. These delivery-chutes are mounted at their rear inner ends upon laterally-projecting supports 354, fixed to the upper ends of uprights 355, which are secured in place upon the cross-bars 34, and the delivery-chutes extend horizontally and forwardly to deliver the completed packages at 100 the front of the machine and are formed with closed bottom and side walls, which latter engage the folded ends of the packages to further crease such folds and to prevent them from becoming unwrapped. The bottoms 105 of the chutes are provided with grooves 356, within which travels a conveyer-chain W, which is continuously driven and which carries at proper intervals to successively eject the packages the upwardly-projecting plates 110 or flights w. Each of the conveyer-chains W is guided at the rear over a pulley 357, mounted upon a bent bracket 358, which is secured to the upright 355.

The wrapping-machine is preferably used 115 in connection with a packing-machine, such as disclosed in Letters Patent No. 660,086, dated October 16, 1900, so that the wrapped

packages are finally deposited in the packing-cases without having any opportunity to become unfolded.

It is obvious that the details of construction may be widely varied by the skilled mechanic without departure from the essentials of the invention and that features of the invention may be used without the adoption of all the parts described.

10 Having described my invention, what I claim as new, and desire to secure by Letters Patent, is—

1. In wrapping-machines, a revoluble shaft for carrying the wrappers in a continuous rolled web, a cutter for severing the separate wrappers from the web, a continuously-rotating set of feed-rollers for withdrawing the web from its roll, an intermittently-rotating set of feed-rollers arranged adjacent the cutter for delivering the wrapper thereto, said sets of feed-rollers being arranged to maintain a slack web portion between them and arranged to maintain a constant grip upon the wrapper-web to prevent the displacement of said slack portion and means for continuously operating said first-mentioned set of rollers and for intermittently and alternately operating said second-mentioned set of feed-rollers and said cutter.

2. In wrapping-machines, a revoluble shaft for carrying the wrappers in a continuous rolled web, a cutter for severing the separate wrappers from the web, a continuously-operated set of feed-rollers comprising a drive-roller and a coöperating, spring-pressed, pressure-roller for withdrawing the web from its roll, an intermittently-operated set of feed-rollers arranged adjacent the cutter for delivering the wrapper-web thereto and comprising a drive-roller and a coöperating, spring-pressed, pressure-roller, said sets of feed-rollers being arranged to maintain a slack web portion between them and to maintain a constant grip upon the wrapper to prevent the displacement of said slack portion, a chute arranged to guide the wrapper-web to said last-mentioned set of feed-rollers and means for operating the drive-roller of each set.

3. In wrapping-machines, the combination with a revoluble shaft for carrying the wrappers in a continuous rolled web and with a cutter for severing the several wrappers from the web, of a continuously-operated set of feed-rollers for withdrawing the wrapper-web from its roll and an intermittently-operating set of feed-rollers for delivering the wrapper-web to the cutter, a guide-grip for engaging and guiding the forward end of the wrapper-web, means for operating said continuously-driven set of feed-rolls and means for operating said intermittent set of feed-rolls and said guide-grip in unison.

4. In wrapping-machines, a pair of revoluble shafts for carrying the inner and outer

wrappers in continuous rolled webs, a cutter for severing the separate wrappers from each of said webs, two sets of continuously-driven feed-rollers geared together and arranged to withdraw the separate wrapper-webs from their respective rolls, two sets of intermittently-driven feed-rollers geared together and arranged to deliver the wrapper-webs to said cutter, each of said sets of feed-rollers being arranged to maintain a constant grip upon the wrapper-web, separate guide-chutes for said inner and outer wrappers having a common outlet adjacent said cutter and means for operating said sets of feed-rollers and said cutter.

5. In wrapping-machines, a revoluble shaft for carrying the wrappers in a continuous rolled web, a continuously-rotating set of feed-rollers for withdrawing the web from its roll, a guide-chute to which the web is delivered by said feed-rollers, a cutter for severing the separate wrapper-sections from the web arranged adjacent the outlet of said guide-chute, an opening in said guide adjacent its outlet end, a pair of intermittently-actuated feed-rollers projecting in opposite directions through the opening in said guide-chute and into engagement with the wrapper-web, both sets of feed-rollers being arranged to maintain a constant grip upon the wrapper-web, means for continuously rotating said first-mentioned set of feed-rollers and means for intermittently and alternately actuating said second set of feed-rollers and said cutter.

6. In wrapping-machines, the combination with a cutter for severing the separate wrappers from a continuous web, of a pair of guide-chutes for the inner and outer wrappers having a common outlet at their inner end adjacent said cutter, openings in said chutes adjacent said outlet and intermittently-operated feed-rolls projecting through said openings into engagement with the wrapper-webs.

7. In wrapping-machines, the combination with a cutter for severing the separate wrappers from a continuous web and with folding mechanism, of two intermittently-operated sets of feed-rolls for delivering the inner and outer wrappers to said cutter and said folding mechanism, each set comprising a drive-roll and a pressure-roll, a main drive-shaft having connections for actuating said cutter, said folding mechanism and one of said drive-rolls, a differential connecting-gear between said drive-rolls, whereby the latter are actuated to feed the wrapper-webs with the forward edge of the outer wrapper projecting beyond that of the inner wrapper.

8. In wrapping-machines, the combination with a cutter and with folding mechanism, of separate feeds for delivering the inner and outer wrapper-webs to said cutter and folding mechanism, a reciprocating grip

for clasping and guiding the forward edges of the wrapper-webs and means for actuating said separate wrapper-feeds at different rates of speed and for simultaneously actuating 5 said guide-grip therewith.

9. In wrapping-machines, the combination with a cutter, of an intermittently-actuated feed for delivering the wrapper-web to said cutter, a brake arranged to engage 10 and arrest the movement of said feed, a drive-shaft and connections thereto for operating said feed, said brake, and said cutter in proper order.

10. In wrapping-machines, the combination 15 with a cutter, of an intermittently-rotated set of feed-rolls for delivering the wrapper-web to said cutter, driving mechanism for alternately operating said feed-rolls and said cutter, said mechanism having a pawl- 20 and-ratchet connection with said feed-rolls, a brake-wheel connected to said rolls, a brake for engaging said wheel and means for applying said brake controlled by said driving mechanism.

11. In wrapping-machines, the combination 25 with a folding mechanism, of a feed for delivering the wrappers to said folding mechanism, a reciprocating grip for engaging and guiding the forward edge of the wrapper and 30 driving mechanism arranged to advance the movement of said feed to move the forward edge of the wrapper into said guide-grip and to subsequently operate said feed and guide-grip in unison.

12. In wrapping-machines, the combination 35 with a folding mechanism, of feed-rolls for delivering the wrapper-web to said mechanism, a fixed cutting edge and reciprocating cutter for severing the separate wrappers 40 from the web, a reciprocating grip for engaging and guiding the forward edge of the wrapper-web, an advance feed for said rolls arranged to move the forward edge of the web into said grip and means for subsequently operating said feed-rolls and grip in 45 unison.

13. In wrapping-machines, the combination 50 with a folding mechanism, of feed-rolls for delivering the wrapper-web to said mechanism, a fixed cutting edge and a reciprocating cutter for severing the separate wrappers 55 from the web, a grip for engaging and guiding the forward edge of the wrapper-web, a reciprocating rack-bar whereon said grip is mounted, a drive-gear engaging said rack and having a pawl-and-ratchet connection with said feed-rolls, an advance-feed arm having a pawl-and-ratchet connection with 60 said feed-rolls and means for actuating said feed-arm and said rack-bar in succession to advance the feed of the rolls and to subsequently operate the same and said guide-grip in unison.

14. In wrapping-machines, the combina-

tion with a folding mechanism, of a set of 65 feed-rolls for delivering the wrapper-web to said folding mechanism, a grip for engaging and guiding the forward edge of the wrapper-web, an advance, pawl-and-ratchet feed for said rolls arranged to move the forward edge 70 of the wrapper into said grip, a main feed for subsequently operating said grip and feed-rolls in unison and having a pawl-and-ratchet connection with the latter, a brake for arresting the momentum of said rolls, a cutter for 75 severing the separate wrappers from the web and means for operating said advance feed, main feed, brake and cutter in succession.

15. In wrapping-machines, the combination 80 with a folding mechanism, of a set of differential feed-rolls for delivering inner and outer wrappers of different lengths from continuous wrapper-webs to said folding mechanism, a reciprocating grip for engaging and 85 guiding the forward edges of the wrapper-webs, actuating means for advancing the feed of said rolls to move the forward edges of the wrapper-webs into said grip and for subsequently actuating said roll and grip in unison and a cutter for severing the separate 90 wrappers from the continuous webs.

16. In wrapping-machines, the combination 95 with a holder within which the article and its wrapper are held during the folding operation, of feed-rolls for delivering the 100 wrapper-web to said holder, a grip for clasping and guiding the forward edge of the wrapper-web over said holder, said grip comprising a reciprocating plate and a spring-pressed jaw pivoted thereto and having a projecting abutment, a fixed cam with which said abutment engages at the proper point for opening said grip and means for operating said feed-rolls and said grip in unison.

17. In wrapping-machines, the combination 105 with a holder for receiving the article and its wrapper during the folding operation, of a grip for clasping and guiding the forward edge of the wrapper over said holder, said grip comprising a reciprocating transverse plate mounted to slide in guideways, a spring-pressed plate having a transverse gripping edge pivoted to said reciprocating plate, said grip-plate and said gripping edge being of a width at least equal to that of the 110 wrapper-web, a projecting abutment on said pivoted grip-plate and a fixed cam with which 115 said abutment engages at the proper point for opening said grip.

18. In wrapping-machines, the combination 120 with a feed for delivering the wrappers from a continuous web, of a transverse cutting edge over which the web is fed, a beveled guide parallel to said edge, a reciprocating rotatable cutter having a portion in rolling contact with said guide, means for actuating said feed and for reciprocating said cutter 125 and yielding connection between said actu-

ating means and said cutter, arranged to force said portion into engagement with said guide.

19. In wrapping-machines, the combination with a feed for delivering the wrappers from a continuous web, of a transverse cutting edge, a beveled guide parallel to and above said edge, a reciprocating rotatable cutter provided with a beveled portion of less diameter than its cutting periphery and having a rolling contact with said guide, actuating means for alternately operating said feed and reciprocating said cutter and yielding connections between said cutter and said actuating means arranged to force said beveled portion into engagement with said beveled guide.

20. In wrapping-machines, the combination with a feed for delivering the wrappers from a continuous web, of a transverse cutting edge, a reciprocating cutting-knife coöperating with said edge to sever the separate wrappers from the continuous web, actuating means for alternately operating said feed and reciprocating said cutter, and a spring-held clamping member arranged to engage said web and having a loose one-way-operating connection with said actuating means.

21. In wrapping-machines, the combination with a feed for delivering the wrappers from a continuous web, of a transverse fixed cutting edge, a guide arranged parallel to and above said edge, and reciprocating rotatable cutting-knife having a rolling contact with said guide and coöperating with said edge to sever the separate wrappers from the continuous web, actuated means for alternately operating said feed and reciprocating said cutter and a transverse, spring-held, clamped member mounted upon a pair of parallel pivoted links and having a loose, one-way pin-and-slot connection with said actuating means.

22. In wrapping-machines, means for severing the separate printed wrapper-sections from a continuous web comprising a cutter, a feed for delivering the web to said cutter and mechanism separate from said feed for timing the relative movements of said web and said cutter, said mechanism being controlled by the successive openings in the wrapper-web which correspond with the separate printed sections thereof.

23. In wrapping-machines, means for severing the separate printed wrapper-sections from a continuous web comprising a cutter, a feed for delivering the web to said cutter, mechanism separate from said feed for timing the relative movements of said web and said cutter, an electrical device for controlling said timing mechanism and means for closing the energizing-circuit of said electrical device at intervals through successive openings in the wrapper-web which correspond to the separate printed sections thereof.

24. In wrapping-machines, the combination with a cutter for severing the separate printed wrapping-sections from a continuous web and with a feed for delivering the web to said cutter, of a correcting stop device arranged to engage the wrapper-web and arrest its forward travel and means for actuating said correcting stop device.

25. In wrapping-machines, the combination with a cutter for severing the separate printed wrapper-sections from a continuous web and with a feed for delivering the web to said cutter, of a correcting stop device for arresting the forward travel of the web and means whereby said stop device is controlled by the movement of the web.

26. In wrapping-machines, the combination with a cutter for severing the separate printed wrapper-sections from a continuous web and with a feed for delivering the web to said cutter, of a correcting stop device arranged to engage the wrapper-web to arrest its forward travel, means whereby said stop device is controlled by the movement of the web and means to alternately operate said feed and cutter and for releasing said stop device.

27. In wrapping-machines, the combination with a cutter for severing the separate printed wrapper-sections from a continuous web and with a feed for delivering the web to said cutter, of a transverse stop-clamp arranged to grip the wrapper-web and arrest its forward travel and means whereby said stop-clamp is controlled by the movement of the web.

28. In wrapping-machines, the combination with a cutter for severing the separate printed wrapper-sections from a continuous web and with a feed for delivering the web to said cutter, of a spring-actuated, pivoted stop-clamp arranged to grip the wrapper-web, a latch for holding said stop-clamp out of operation, means whereby the release of said latch is controlled by the movement of the web and means for alternately operating said feed and cutter and for throwing said stop-clamp out of operation and into reengagement with said latch.

29. In wrapping-machines, the combination with a cutter for severing the separate printed wrapper-sections from a continuous web and with a feed for delivering the web to said cutter, of a correcting-stop for arresting the forward travel of the web, an electrical device for controlling said stop and means for closing the energizing-circuit of said electrical device at intervals corresponding to the feed of the several printed sections of the wrapper-web.

30. In wrapping-machines, the combination with a cutter for severing the separate printed wrapper-sections from a continuous web and with a feed for delivering the web to said cutter, of a transverse stop-clamp ar-

ranged to grip the wrapper-web and arrest its forward travel, an electromagnet for controlling said stop-clamp and a spring-pressed contact-arm arranged to engage openings in the wrapper-web and closing the circuit through said magnet.

31. In wrapping-machines, the combination with a cutter for severing the separate printed wrapper-sections from a continuous web and with a feed for delivering the web to said cutter, of a transverse stop-clamp arranged to grip the wrapper-web and arrest its forward travel, an electromagnet for controlling said stop-clamp, a spring-pressed contact-arm arranged to engage openings in the wrapper-web and closing the circuit through said magnet and means for adjusting the position of said contact-arm.

32. In wrapping-machines, the combination with a cutter for severing the separate printed wrapper-sections from a continuous web and with a feed for delivering the web to said cutter, of a pivoted, spring-pressed stop-clamp arranged to grip the wrapper-web, a latch for holding said stop-clamp out of operation, an electromagnet for releasing said latch, a spring-pressed contact for closing the energizing-circuit of said magnet, a drive-shaft, and operating connections therewith for alternately actuating said feed and reciprocating said cutter and for throwing said stop-clamp out of operation into reengagement with said latch.

33. In wrapping-machines, the combination with a cutter for severing the separate printed wrappers from a continuous web and with intermittently-operated feed-rolls for delivering the web to said cutter, of a correcting stop device for arresting the travel of the web, comprising a transverse grip arranged to engage the web and mounted between a pair of rock-arms, a rock-shaft whereon said arms are mounted, a spring for actuating said shaft, a stop-arm connected to said shaft, a latch engaging said stop-arm to hold said grip out of operation, a magnet arranged to release said latch, a spring-contact for closing the energizing-circuit of said magnet arranged to engage openings in the wrapper-web and means for throwing said stop-arm into reengagement with said latch.

34. In wrapping-machines, the combination with a cutter for severing the separate inner and outer wrappers from continuous webs and with intermittently-operating feed-rolls for delivering the webs to said cutter, of separate guide-chutes for said web, separate connected stop-clamps arranged to engage said webs, an electromagnet controlling said stop-clamps and means controlled by the travel of one of said webs for closing the energizing-circuit of said magnet.

35. In wrapping-machines, the combination with a cutter for severing separate printed wrapper-sections from a continuous web

and with a feed for delivering the web to said cutter, of a stop device for arresting the forward travel of the web and means whereby said stop device is controlled by the openings in the wrapper-web which correspond to the separate printed sections thereof.

36. In wrapping-machines, the combination with a cutter for severing the separate printed wrapper-sections from a continuous web and with a feed for delivering the web to said cutter, of a stop device for arresting the forward travel of the web, an electrical device for controlling said stop device and means for closing the energizing-circuit of said electrical device at intervals through openings in the wrapper-web corresponding to the separate printed sections thereof.

37. In wrapping-machines, the combination of a vertically-disposed open-ended folding-chute, a feed for delivering the wrappers over said chute, a pair of vertical, spring clamping-plates above said chute for holding one of the articles over said chute and wrapper, an article-feedway, a plunger horizontally reciprocating across said feedway and at right angles to said chute for moving the articles from the feedway into the grasp of said clamping-plates and a second plunger vertically reciprocating in line with said chute for moving the article from between said clamping-plates and projecting it together with its wrapper into said chute.

38. In wrapping-machines, the combination of a vertical, open-ended folding-chute, a feed for delivering the wrapper over the top of said chute, a pair of vertical oppositely-disposed clamping-plates of spring metal above said chute for holding the article over said chute and wrapper, an article-feedway having an endless conveyer-belt and a stop above said belt for arresting the movement of the articles therein, a horizontally-reciprocating plunger for moving the articles from said feedway into the clasp of said clamping-plates, a vertically-reciprocating plunger for moving the articles from between said plates and projecting it together with its wrapper into said chute.

39. In wrapping-machines, a stationary, vertically-disposed folding-chute having an open top and open bottom, a feed for delivering the wrappers over said chute, a pair of vertically-disposed spring clamping-plates above said chute for holding the article over said chute and wrapper, a horizontal, article-feedway having bottom and side walls and arranged in the same horizontal plane with said clamping-plates, a conveyer-belt traveling in said feedway, a stop for arresting the movement of the articles in said feedway, openings in the side walls of said feedway opposite said clamping-plates, a plunger horizontally reciprocating across said feedway and through said openings for moving the articles therefrom into the grasp of said

clamping-plates and a vertically, reciprocating plunger for moving the articles from the clasps of said plates and projecting it, together with its wrapper into said folding-chute.

40. In wrapping-machines, separate folding mechanisms each comprising suitable folders and a holder for the article to be wrapped, the holders in said separate folding mechanisms being spaced apart in accordance with one of the dimensions of the article, a single-article feedway for said separate folding mechanisms and separate carriers correspondingly spaced apart in accordance with one of the dimensions of the article for projecting separate articles from said feedway to the holders of said separate folding mechanisms.

41. In wrapping-machines, separate folding mechanisms each comprising a stationary folding-chute and folders, said folding-chutes being spaced apart in accordance with one of the dimensions of the article to be wrapped, a single-article feedway for said folding mechanisms, means for arresting the movement of the articles through said feedway with one of the articles opposite each of said folding mechanisms and separate carriers moving transversely across said feedway and correspondingly spaced apart in accordance with one of the dimensions of the articles to be wrapped for projecting separate articles from the feedway to said separate folding mechanisms.

42. In wrapping-machines, the combination with separate folding mechanisms, of a single, substantially horizontal feedway for the articles to be wrapped, a conveyer for moving the articles along said feedway, a stop for arresting the travel of the same and separate carriers moving transversely across said feedway for projecting separate articles therefrom to said separate folding mechanisms.

43. In wrapping-machines, the combination with separate folding mechanisms, a horizontal feedway for the articles to be wrapped, a feed-belt moving on the bottom thereof, openings in said feedway opposite said separate folding mechanisms, a stop for arresting the travel of the articles with separate ones opposite said openings and a pair of reciprocating plungers for projecting the articles arrested opposite said openings into said separate folding mechanisms.

44. In wrapping-machines, the combination with separate vertically-disposed folding-chutes, of a pair of grip-plates over each of said chutes for holding the articles to be wrapped, a wrapper-feed mechanism for delivering the wrappers intermediate each of said chutes and said grip-plates, a horizontally-disposed feedway for the articles having openings opposite each pair of grip-plates, a conveyer-belt in said feedway, a stop there-

in for arresting the movement of the articles with separate ones opposite said openings, a pair of horizontally-reciprocating plungers for projecting the articles opposite said openings into the clasp of said grip-plates and a pair of vertically-reciprocating plungers for projecting the articles together with their wrappers into said folding-chutes.

45. In wrapping-machines having a set of folders, a folding-chute about which the folders are grouped and in which the article is held during the folding operation, said chute comprising a pair of fixed, adjacent side and end walls and an opposite pair of adjacent spring-pressed side and end walls, whereby the articles are yieldingly held in accurate position during the folding operation.

46. In wrapping-machines, a horizontal bed-plate, an opening in said bed-plate, a vertically-disposed folding-chute arranged below said opening, said folding-chute comprising side and end walls, the upper edges of said end walls being spaced apart from the upper face of said bed-plate a distance equal to the thickness of one of the articles to be wrapped, oppositely-disposed top-folders mounted to slide upon the top of said bed-plate and over the opening of said chute, oppositely-disposed end-folders mounted independently of said top-folders beneath said bed-plate and arranged to move over the top edges of the folding-chute ends, means for successively projecting the articles and their wrappers through said folding-chute, a drive-shaft and independent operating connections between said shaft and said top and end folders.

47. In wrapping-machines, the combination with a set of folders, of an open-ended chute about which the folders are grouped and in which the articles are held during the folding operation, said chute comprising side walls, one of which is spring-held and pivoted at its outer end, and an inclined pressure-plate of spring-metal fixed at one end to the inner end of said spring-pressed side wall and extending within the chute.

48. In wrapping-machines, the combination with a set of folders, of an open-ended folding-chute about which the folders are grouped and within which the article is held during the folding operation, said chute having side and end walls, one of each pair of adjacent side and end walls comprising a spring-held plate pivoted at its outer end and having a pressure-plate of spring-metal fixed at one end to the inner, free ends of said pivoted plate and projecting outwardly within the chute, means for feeding the article and its wrapper to said chute and means for operating the folders.

49. In wrapping-machines, the combination with a holder and with means for feeding the articles and wrappers thereto, of oppositely-extending abutments at the ends of

said holder, end-folders, arranged to engage said abutments and parallel actuating and guiding rock-arms swinging on centers out of line and connected to said end-folders.

- 5 50. In wrapping-machines, the combination with a holder and with means for delivering the article and its wrapper thereto, of oppositely-extending abutments at each end of said holder, oppositely-disposed pairs of 7c
10 end-folders, a support for each pair of folders, and means for actuating and guiding each of said supports inwardly and outwardly against said abutments, comprising a pair of actuating rock-arms between the free ends of which 15 said support is pivoted and a third guiding rock-arm parallel to said pair of rock-arms and also pivoted at its free end to said support said actuating and said guiding rock-arms swinging respectively on centers out of 20 line.

51. In wrapping-machines, the combination with a holder and with means for delivering the article and its wrapper thereto, of oppositely-extending abutments at each end 25 of said holder, end-folders, each of said folders comprising a side portion arranged to engage the end of the package and a laterally-extending portion arranged to engage said abutment and parallel actuating and guiding 30 rock-arms swinging respectively on centers out of line and connected to said folders.

52. In wrapping-machines, the combination with a folding box or chute, and with means for delivering the article and its wrapper thereto, said box or chute having laterally and outwardly projecting ledges spaced apart from the inner end of the same, oppositely-disposed pairs of rocking end-folders and means for moving said end-folders inwardly and outwardly against the ends of 40 the article and against said ledges.

53. In wrapping-machines, the combination with a wrapper-feed and an article-feed, of an open-ended folding-chute, means for 45 projecting the article and its wrapper into said chute, the latter having laterally and outwardly projecting end ledges spaced apart from the inner end of the same, oppositely-disposed pairs of rocking end-folders, each 50 pair being mounted between a pair of rock-arms and means for moving said end-folders inwardly and outwardly against the ends of the article and against said ledges.

54. In wrapping-machines, the combination with a holder and with means for feeding the article and its wrapper thereto, of reciprocating side-folders, end-tuckers reciprocating at right angles to the path of movement of said side-folders, oppositely-disposed 60 pairs of movable end-folders and means for operating said end-tuckers means for slightly advancing both pairs of said end-folders before said end-tuckers are withdrawn to hold the end fold and for subsequently actuating

each pair in succession to complete the end 65 fold.

55. In wrapping-machines, a horizontal bed-plate having an opening therein, a vertically-disposed, folding-chute below said opening, said chute having an open top and an open bottom and adapted to contain two or more of the articles during and after the wrapping operation, a single plunger for successively feeding the articles and their wrappers into said chute through its open top and 75 for finally projecting the completely-wrapped articles from the lower open bottom of said chute, a horizontal delivery-chute arranged at right angles to and opposite the open bottom of said folding-chute and directly beneath said horizontal bed-plate, into which the completed packages are finally ejected by the operation of said plunger, said delivery-chute having side walls for engaging 80 the folded ends of said packages and means 85 separate from said plunger for moving the articles through said delivery-chute.

56. In wrapping-machines, a horizontal bed-plate having an opening therein, a vertically-disposed folding-chute beneath said 90 opening, said chute having an open top and an open bottom, a vertically, reciprocating plunger for successively feeding the articles and their wrappers through the open top of said chute and for ejecting the completed articles 95 from said chute through its open bottom, folders about said chute, a horizontally-disposed delivery-chute arranged directly beneath the said horizontal bed-plate and below the open bottom of said folding-chute 100 into which delivery-chute the articles are finally ejected by the operation of said plunger and a conveyer traveling in said delivery-chute having flights or projections for engaging and moving the completed articles from 105 beneath said folding-chute.

57. In wrapping-machines, the combination with the folding mechanism, of a rotatable shaft D for carrying the wrapper in a rolled web, drive feed-roll 44 and coöperating 110 pressure-roll 45 for withdrawing the wrapper-web from its roll, guide-chute F for the wrapper-web, feed-roll 75 and coöperating pressure-roll 76 arranged adjacent the inner end of said guide-chute F, a cutting edge f" arranged adjacent the inner end of said chute 115 a reciprocating cutter F' coöperating therewith for separating the separate wrappers from the web, drive-shaft B and connections therewith for continuously rotating feed-rolls 44, 45 and for alternately rotating feed-rolls 75, 76 and reciprocating cutter F'.

58. In wrapping-machines, the combination with the folding mechanism, of a rotatable shaft D for carrying the wrapper in a 125 rolled web, drive feed-roll 44 and coöperating pressure-roll 45 for withdrawing the wrapper-web from its roll, guide-chute F for the wrap-

per-web having a transverse opening adjacent its inner end, feed-roll 75 and coöperating pressure-roll 76 projecting through said opening into engagement with the web, a cutting edge f'' arranged adjacent the end of said chute, a reciprocating cutter F' coöperating therewith for separating the separate wrappers from the web, drive-shaft B and connections therewith arranged to continuously rotate feed-rolls 44, 45 and to alternately rotate feed-rolls 75, 76 and reciprocate cutter F'.

59. In wrapping-machines, the combination with the folding mechanism, of feed-rolls 75 and 85 and coöperating pressure-rolls 76 and 89 for delivering the outer and inner wrappers to said folding mechanism, gears 116 and 117 of different sizes and intermediate idler 118, connecting feed-rolls 75 and 85, shaft 73 whereon roll 75 is mounted, ratchet 98 fixed to said shaft, gear 96 loose on said shaft and having pawl 99 engaging said ratchet and reciprocating rack-bar 100 engaging gear 96.

60. In wrapping-machines, the combination with the folding mechanism, of feed-roll 75 and coöperating pressure-roll 76 for delivering the wrapper to said mechanism, shaft 73 whereon roll 75 is mounted, advance-30 feed arm 162 and gear 96 loose on said shaft and each having pawl-and-ratchet connections therewith, rack-bar 100 engaging gear 96, a grip for engaging and guiding the forward edge of the wrapper, comprising trans-35 verse plate H mounted on rack-bar 100 and spring-held grip-jaw h pivoted to plate H and having an abutment 157, fixed cam 158 with which said abutment engages and drive-shaft B having operating connections with 40 arm 162 and rack-bar 100.

61. In wrapping-machines, the combination with separate folding-chutes C, C', of the separate pairs of feed-rollers 75 and coöperating pressure-rollers 76 for feeding the wrappers to said chute, a common shaft 73 upon the opposite ends of which said rollers 75 are mounted, a gear 96 loosely mounted in central position upon said shaft, a pawl-and-ratchet connection between gear 96 and shaft 50 73, a reciprocating rack-bar 100 engaging said gear, guide-grip plate H centrally mounted upon said rack-bar and carrying on each side of said rack-bar a spring-held, pivoted grip-jaw h' for engaging the forward edge of 55 the wrapper and actuating connections for said rack-bar whereby both sets of feed-rollers and said guide-grip plate are operated in unison.

62. In wrapping-machines, the combination with the folding mechanism and with the feed-rolls for delivering the wrapper-web thereto, of guide-chute F for the wrapper-web, fixed clamp-plate 181 and coöperating spring-held stop-clamp 186 arranged adja-

cent said chute, stop-arm 195 connected to 65 said clamp, latch J engaging said arm to hold said clamp out of operation; electromagnet J for tripping said latch and spring-held contact-finger 209 projecting through an opening in said chute and through openings in the 70 wrapper-web to close the circuit of said magnet.

63. In wrapping-machines, the combination with folding mechanism and feed-rolls for delivering the wrapper thereto, of fixed 75 cutting edge f'' , beveled guide 129 parallel to said edge, rotating cutter F' provided with beveled abutment 131 having a rolling contact with said beveled guide, reciprocating carrier 125, supporting-block 126 for said 80 cutter mounted to slide in guideways 127 fixed to said carrier, cushion-spring connections between said block and carrier for forcing said beveled abutment into engagement with said beveled guide and actuating means 85 connected to said carrier.

64. In wrapping-machines, the combination of bed-plate A, openings a, a' therein, folding-chutes C, C' below said openings, means for feeding the wrappers over said 90 chutes, the pairs of grip-plates N for supporting the articles above said chutes, feedway K, endless conveyer-belt k therein, stop-plate 250, the pair of plungers M, M' horizontally reciprocating at right angles to said feedway 95 for projecting the articles therefrom into the clasp of said grip-plates, the pair of vertically-reciprocating plungers O, O' for moving the articles from the clasp of said grip-plates and projecting the same together with their 100 wrappers into folding-chutes C, C', cross-head 255 common to plungers M, M', cross-head 264 common to plungers O, O' and means for guiding and reciprocating said 105 cross-heads.

65. In wrapping-machines, the combination of bed-plate A, openings a, a' therein, folding-chutes C, C' below said openings, a feed for delivering the wrappers over said chutes, a support mounted upon said bed-plate above said chutes, the pairs of grip-plates N, N, upon said supports over said 110 chutes, a feed for delivering the articles to said pairs of grip-plates, a pair of vertically-reciprocating plungers O, O' carried on said supports above said chutes, for moving the articles from said grip-plates and projecting them together with their wrappers into said chutes, the pairs of front and rear side-folders P, P' and Q, Q', pairs of end-folders S, S' and 115 T, T', means for operating said folders, the pairs of end-tuckers R, R and R', R' carried on said support, cross-head 264 common to said plungers, cross-head 316 common to 120 said pairs of end-tuckers and means for guiding and operating said cross-heads.

66. In wrapping-machines, an open-end 125 ed folding-chute C comprising adjacent fixed

side and end walls and oppositely-arranged adjacent side and end walls formed respectively of plates 279 and 289 pivoted at the outer end of said chute and spring-metal, inclined plates 283 and 292 fixed to the inner, free ends of said pivoted plates and projecting into said chute, springs 286 arranged between each of said pivoted plates and a fixed part, guiding-pins 284, whereon said springs are mounted, fixed to each of said plates and extending through said fixed parts and adjusting-nuts 285 threaded on said pins.

67. In wrapping-machines, the combination of a vertically-disposed chute C having the fixed end wall 278 and the spring-pressed end wall 279, the upper edges of which are spaced apart from the upper end of said chute, oppositely-projecting ledges 287 and 293 secured respectively to the upper edges of said side walls, the latter being pivoted to end wall 289 and having means for guiding it in straight-line direction, and the oppositely-disposed pairs of end-folders S, S and T, T, each comprising a side portion 336 and outwardly-projecting flange portions 337 and arranged to form and crease the end fold on said ledges.

68. In wrapping-machines, the combination of bed-plate A, folding-chute C, oppositely-disposed reciprocating side-folders P and Q mounted to slide on said bed-plate, guides for said folders, cross-heads 302 and 303 mounted beneath said bed-plate, guideways 301 for said cross-heads fixed to the under face of said bed-plate, pins 305 fixed to said folders, projecting through slots in said bed-plate and engaging laterally-extended slots in said cross-heads and operating means for the latter.

69. In wrapping-machines, the combination of bed-plate A, openings a, a' therein, folding-chutes C, C' projecting therefrom, oppositely-disposed pairs of rear and front side folders P, P' and Q, Q', guides for said folders, cross-heads 302 and 303 mounted beneath said table, guideways 301 for said cross-heads fixed to the under face of said bed-plate, connecting-pins 305 between said folders and cross-heads projecting through slots in said bed-plate, drive-shaft B, a cam 313 thereon, bell-cranks 309 and 308 operated by said cam and connecting-links 307 between said bell-cranks and said cross-heads.

70. In wrapping-machines, the combination with a horizontal bed-plate A, the openings a, a' therein; vertically-disposed folding-chutes C, C' below said openings, the set of rear end-folders S, S and S', S', the set of front end-folders T, T and T', T', a support

for each set of end-folders carried between a pair of rock-arms, rock-shafts 328 and 342 whereon said pairs of rock-arms are respectively mounted, a drive-shaft B, a cam 350 thereon, and connecting-links 347 and 351 65 between said cam and said rock-shafts.

71. In wrapping-machines, the combination with the horizontally-disposed bed-plate A, the opening a therein, the vertical folding-chute C below said opening, continuously-operated feed-rolls 44, 45 for the wrapper-web, intermittently-operated feed-rolls 75, 76 for delivering the web over said chute, a guide-grip H, reciprocating rock-bar 100, arranged to operate feed-rolls 75, 76 and guide-grip H, cutter F' for severing the separate wrappers from the web, a pair of grip-plates N over said chute, feedway K having a feed-belt k, plunger M for feeding the articles from said feedway to said grip-plates, vertically-reciprocating plunger O for projecting the article and its wrapper into said chute, oppositely-disposed reciprocating side-folders P, Q, a pair of end-tuckers R, R, oppositely-disposed pairs of end-folders S, S and T, T, 85 delivery-chute W below said folding-chute, conveyer w in said chute, a drive-shaft B and connections therewith for operating said devices.

72. In wrapping-machines, the combination with the bed-plate A, the open-ended folding-chute C, C' below said bed-plate, the duplicate sets of feed-rolls 75, 76, reciprocating guide-grip plate H, having duplicate grip-jaws h, h, reciprocating rack-bar 100 arranged to actuate said feed-rolls and said guide-grip, the pairs of grip-plates N above said chutes, feedway K, feed-belt k therein, stop-plate 250 for arresting the travel of the articles in said feedway, duplicate plungers 100 M, M connected by cross-head 255 for projecting articles from said feedway into the clasp of said grip-plates, plungers O, O' connected by cross-head 264 for moving the articles from said grip-plates and projecting the 105 same together with their wrappers into said folding-chutes, duplicate pairs of front and rear side-folders P, P' and Q, Q' connected by cross-heads 302 and 303, the pairs of end-tuckers R, R and R', R' connected by cross-head 318, the pairs of rear end-folders S, S and S', S' on support 330, the pairs of front end-folders T, T and T', T' on support 340, drive-shaft B and connections operated thereby for each of said cross-heads, said 110 rack-bar and each of said supports.
